[57] CLAIM

The ornamental design for an electrical connector housing, substantially as shown and described.

DESCRIPTION

FIG. 1 is a top view of an electrical connector housing showing our new design;

FIG. 2 is a bottom view thereof;

FIG. 3 is a side view thereof;

FIG. 4 is an end view taken from the left side of FIG. 3. The end opposite FIG. 4 is a hollow cylinder being plain and unornamented.

FIG. 1

FIG. 2

FIG. 3

FIG. 4
